UNITED STATES PATENT OFFICE.

DANIEL F. McGOVERN, OF MONTPELIER, VERMONT.

POLISHING WHEEL.

1,416,729.

Specification of Letters Patent. Patented May 23, 1922.

Application filed May 13, 1921. Serial No. 469,094.

To all whom it may concern:

Be it known that DANIEL F. McGOVERN, a citizen of the United States, residing at Montpelier, county of Washington, State 5 of Vermont, has invented certain new and useful Improvements in Polishing Wheels, of which the following is a specification.

My present invention relates to certain improvements in stone polishing wheels and 10 particularly to those wheels for imparting the initial polish to a stone surface by an abrasive such as chilled shot, as distinguished from emery polishing.

As illustrative of my invention I have 15 shown one of my wheels, the same being in its general form the type shown in my prior Patent No. 1,296,985, of March 11, 1919. In this wheel a great practical advantage was gained in the use of two sets 20 of concentric flanges of substantially semi-circular extent, each set being offset slightly on the cover disc or plate which is characteristic of this type of wheel.

The construction referred to has proven 25 very advantageous in that it embodies long continuous flange surfaces of great feeding capacity as well as of great efficiency in their oscillating movement which is the working movement effecting the abrasive 30 action on the stone.

The great difficulty, however, in all wheels 35 of this type has been to secure a proportioning of the two opposed factors in the movement of the abrasive under the wheel. These two movements should be considered as they underlie the principles of my present invention.

It will be seen that inasmuch as these 40 wheels must feed or draw the abrasive inward to have it available for the working edges of the flanges, there must be a constant tendency of the material to travel inward towards the center of the wheel. At the same time the abrasive when under 45 flanges has a tendency to work out, due to the rotative action of the wheel as a whole. The movement of the body of abrasive is therefore a double movement and as these tendencies are opposed, it is of the greatest 50 importance that they be balanced in so far as possible so as to secure a maximum of efficiency through equality of distribution.

One other factor must furthermore be

noted before passing to the discussion of my present invention. This factor is that 55 of the variable speed of different portions of the wheel considered radially. That is to say, the outer portions of the wheel travel at a rapid rate while the inner portions of the wheel nearer the center have comparatively slight movement. This has caused 60 in a great many commercial wheels, a choking tendency near the center which has prevented the operation of the wheel and necessitated frequent over turnings in order 65 to dislodge the shot and mud from the channels in which it has become packed.

As illustrative of my invention I have endeavored to show in the accompanying drawings, a structure of my present improvement and to illustrate its action and the above mentioned theory in a necessarily somewhat diagrammatic manner. Throughout the specification and drawings the usual reference characters are applied to 75 represent corresponding parts, and in the drawings:

Fig. 1 is a section through adjacent flanges showing the action of the shot during rotation, and

Fig. 2 is a face view of the wheel in accordance with my invention.

Referring to the wheel shown in my drawings, it will be noted in general that there are two sets of substantially concentric half 85 circle flanges 4, 5, 6, 7 and 8, and 4', 5', 6', 7' and 8'. These sets are slightly off center with regard to the central aperture 2 in the plate 1 to which the flanges are attached and which overlies and gives draft 90 to the wheel.

Furthermore, as characteristic of this wheel it will be noted that the two flanges 4 and 5 constitute in reality feeders whose first and immediate function is to draw in 95 the abrasive from the edge of the wheel by the action of their runner shaped ends a, passing it along to the channels 6', 7' and 8' which are in the opposite set. Of course it will be understood that all of the flanges at 100 all times are supposed to have their working edges acting on the abrasive which while rolling along the flanges for certain distances eventually is worked out by the centrifugal action towards the edge of the wheel. The 105 body of the shot, however, works inwardly,

being scooped by the inner faces of the flanges as it is passed inward.

In order to assure an adequate supply to the inner portions of the wheel, this body of shot within the channels must of necessity be somewhat in excess of the amount actually required to cover the surface of the work under the flanges. The result therefore is that there is certain at times to be a considerable excess of shot passed into the central channels of the wheel which unless otherwise accommodated chokes the channels as before described.

I have discovered that by reason of the relatively lower speed of the inner regions of the wheel I am able to secure a return of this excess of abrasive by simply providing interruptions or openings in the lower edges of the interior flanges through which excess abrasive may pass radially outward to the feed flanges and thus circulate within the wheel itself without danger of clogging and assuring at all times ample amounts of abrasive adjacent the channel edges in all portions of the wheel.

I have shown in the drawings such apertures indicated at A. In the specific form shown these are cut through the flanges 6 and 7 and 6' and 7' in slightly staggered relation. I have indicated by the arrow X the inward feed of the abrasive and by the arrow Y the outward movement of excess abrasive through the apertures A. So constructed the efficiency of the wheel is very materially increased and its working capacity very much enlarged. The apertures should be somewhat proportioned to the diameter of the wheel and their number may possibly be varied, although I find that a single aperture in each of the two flanges mentioned in my own wheel seems to give maximum efficiency.

My invention may be applied to a variety of types of wheel, but is I believe, especially effective in such a wheel as that shown in which there are long substantially continuous feeding flanges delivering to an interior group of work flanges of substantially continuous character and whose action is

slightly eccentric to the rotation of the wheel 50 on its axis.

What I therefore claim and desire to secure by Letters Patent is:

1. A polishing wheel comprising a plate having on its working face a plurality of spaced flanges, the space between the outer pair of flanges defining an uninterrupted abrasive feed channel and an inner pair of flanges included by said outer pair having openings between their ends for the radial return of the abrasive to said feed channel, the opening in one of said flanges being staggered with relation to the opening of the other flange.

2. A polishing wheel comprising a plate having on its working face a plurality of spaced flanges, the space between the outer pair of flanges defining an uninterrupted abrasive feed channel and an inner pair of flanges included by said outer pair having openings between their ends terminating short of the under face of the plate and permitting the radial return of the abrasive to said feed channel, the opening in one of said flanges being staggered with relation to the opening of the other flange.

3. A polishing wheel comprising a plate having on its working face duplicate sets of spaced substantially concentric segmental flanges, the centers of said sets being relatively offset, and the spaces between the outer pair of flanges of each set defining uninterrupted abrasive feed channels progressing towards the center of the plate, a pair of the flanges of each set included by said outer pair of flanges having openings between their ends for the radial return of the abrasive to said feed channels, and the opening in one flange of each pair being relatively staggered with relation to the opening in the adjacent flange of said flange pair.

In testimony whereof I affix my signature in presence of two witnesses.

DANIEL F. McGOVERN.
